DESIGN.

G. S. WARD.

PARAFFIN PAPER WRAPPER FOR A LOAF OF BREAD.

53,261.

APPLICATION FILED SEPT. 16, 1914. Patented Apr. 29, 1919.

UNITED STATES PATENT OFFICE.

GEORGE S. WARD, OF NEW YORK, N. Y., ASSIGNOR TO WARD BAKING COMPANY, OF NEW YORK, N. Y., A CORPORATION OF NEW YORK.

DESIGN FOR A PARAFFIN-PAPER WRAPPER FOR A LOAF OF BREAD.

53,261.

Specification for Design.

Patented Apr. 29, 1919.

Application filed September 16, 1914. Serial No. 862,112. Term of patent 14 years.

To all whom it may concern:

Be it known that I, GEORGE S. WARD, a citizen of the United States, and a resident of the city, county, and State of New York, have invented a new, original, and ornamental Design for Paraffin-Paper Wrappers for Loaves of Bread, of which the following is a specification, reference being had to the accompanying drawing, forming part thereof.

The figure is a plan view of the wrapper showing my design.

I claim:

The ornamental design for a paraffin-paper wrapper for a loaf of bread as shown.

GEORGE S. WARD.

Witnesses:

M. SHAW,
E. LORD.
